(57) **CLAIM**

The ornamental design for a bottle, as shown and described.

DESCRIPTION

FIG. 1 is a top, front, right side perspective view of a bottle showing a first embodiment of our new design;
FIG. 2 is a front elevational view thereof;

FIG. 3 is a right side elevational view thereof;
FIG. 4 is a rear elevational view thereof;
FIG. 5 is a left side elevational view thereof;
FIG. 6 is a top plan view thereof;
FIG. 7 is a bottom plan view thereof;
FIG. 8 is a bottom, front, right side perspective view thereof;
FIG. 9 is a top, front, right side perspective view of a bottle showing a second embodiment of our new design;
FIG. 10 is a front elevational view thereof;
FIG. 11 is a right side elevational view thereof;
FIG. 12 is a rear elevational view thereof;
FIG. 13 is a left side elevational view thereof;
FIG. 14 is a top plan view thereof;
FIG. 15 is a bottom plan view thereof;
FIG. 16 is a bottom, front, right side perspective view thereof;
FIG. 17 is a top, front, right side perspective view of a bottle showing a third embodiment of our new design;
FIG. 18 is a front elevational view thereof;
FIG. 19 is a right side elevational view thereof;
FIG. 20 is a rear elevational view thereof;
FIG. 21 is a left side elevational view thereof;
FIG. 22 is a top plan view thereof;
FIG. 23 is a bottom plan view thereof;
FIG. 24 is a bottom, front, right side perspective view thereof;
FIG. 25 is a top, front, right side perspective view of a bottle showing a fourth embodiment of our new design;
FIG. 26 is a front elevational view thereof;
FIG. 27 is a right side elevational view thereof;
FIG. 28 is a rear elevational view thereof;
FIG. 29 is a left side elevational view thereof;
FIG. 30 is a top plan view thereof;
FIG. 31 is a bottom plan view thereof; and,
FIG. 32 is a bottom, front, right side perspective view thereof.
The dash-dash-dash-type broken lines shown in the drawing views are included for the purpose of illustrating environmental structure and form no part of the claimed design.
The dot-dash-dot-dash-dot-dash type broken lines shown in the drawing views define the unclaimed boundaries of the claimed design.
